L. C. BAYLES

TAR EXTRACTOR

Filed April 26, 1924

INVENTOR

Lewis C. Bayles.

BY
Herbert C. Ogden
HIS ATTORNEY

UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

TAR EXTRACTOR.

Application filed April 26, 1924. Serial No. 709,113.

To all whom it may concern:

Be it known that I, LEWIS C. BAYLES, a citizen of the United States, and a resident of Easton, county of Northampton, and 5 State of Pennsylvania, have invented a certain Tar Extractor, of which the following is a specification, accompanied by drawings.

This invention relates to exhausting apparatus such as centrifugal blowers and 10 the like. More particularly the features of invention have reference to blowers and ex- hausters which are adapted to operate on fluid such as illuminating gas and the like which hold in suspension heavy liquid or 15 semisolid matter such as tar.

One object of this invention is to separate and extract tar and similar heavy substances from the gas during the exhausting of the gas. This object is accomplished in 20 the preferred form of the invention by directing the gas at a high velocity in a curved path. The greater momentum of the heavy substances causes them to be projected in more nearly a straight line toward 25 an adjacent chamber in which they may collect to be drawn off.

The invention will be more clearly understood by reference to the following description and the accompanying drawings in 30 which there is shown an improved form which the invention may assume in practice. The drawing is a longitudinal sectional ele- vation of a blower and exhauster in which the apparatus for separating coal tar from 35 the gas is included as an integral part.

The exhauster is preferably of the centrifugal blower type, having a casing A which may, if desired, be formed in two or more sections, the lower portion being pro- 40 vided with an inlet B for connection with a supply pipe C. An outlet D is also formed integrally with the casing A and is adapted to be attached in any suitable manner to an outlet pipe E. A pair of journals F mounted on brackets G support a rotating shaft H. Impellers J preferably of the open type are mounted on the shaft H and are adapted to rotate between shrouds K formed integrally with or secured in the casing A. 45 There may be as many impellers J provided as desired, in the present instance there being two, it being understood that the blower may be single or multi-stage. The blower is adapted to draw the gas from the 50 inlet B into a chamber L at the entrance to

the impellers J and by means of the first stage impeller to project the gas between the shrouds K through a diffuser throat O into an intermediate pressure chamber P leading to the entrance of the second stage im- 60 peller J by which the gas is further com- pressed and impelled at high pressure through the second stage diffuser O' into the chamber Q leading to the outlet D.

The gas acted on by the impellers J is 65 projected into the diffuser O at a high ve- locity. Tar or heavier matter carried in sus- pension is projected with the gas, but on account of the increasing radius of the diffuser O and the increasing cross sectional 70 area thereof, the velocity of the gas decreases as it approaches the intermediate pressure chamber P. The heavier matter in the gas, however, having greater momentum than the gas, will be projected in a generally 75 straight line radially while the gas more readily flows around the curved end R of the diffuser O to enter the pressure chamber P. To receive the tar and heavier matter, the casing is slotted as at S in line with the 80 straight portion of the diffuser O. An an- nular chamber T into which the slot S leads is adapted to collect the tar and permit the same to flow by gravity to a sump U from 85 which it may be drawn off through a pipe V provided with a valve W.

Part of the tar may pass the slot S and be carried into the second stage of compression and accordingly the second stage diffuser throat O' is provided with a slot X similar 90 to the slot S and an annular chamber Y communicating with the slot to conduct the tar to a sump Z located at a low point in the casing A. Likewise, a pipe a and a valve b are provided to drain the sump Z. 95

Throughout the course of the flow of gas suitable baffles are provided to prevent and check turbulence in the current. A baffle c in the inlet B and smaller vanes d check and cross currents in the flow of gas to the first stage impeller J. Additional vanes e in the inlet chamber L also assists in pre- 100 venting such cross currents. Radially dis- posed baffles f in the intermediate pressure chamber P direct the current of gas to the second stage impeller J. Likewise, baffles g in the chamber Q and a baffle h in the outlet D direct the gas with a minimum of cross currents into the pipe E.

A suitable gasket j between the shrouds 110

- K and a collar k on the shaft H prevents leakage from the intermediate pressure chamber P and the space behind the impellers J. As the pressures on opposite faces of the impeller J are not the same, causing an unbalance, there is provided a counter-balance drum o which on its inner side is exposed to the same pressure as the back faces of the second stage impeller J.
- 10 The outer face of the drum o is exposed to a negative pressure in a cylindrical chamber p which communicates by means of a pipe q with the inlet B.
- 15 Labyrinth seals r for the shaft H are provided to prevent the escape of gas from the casing. A chamber s adjacent the seal r is adapted to prevent air leakage at the intake end of the shaft H, there being provided a pipe t leading to the inlet B to fill said chamber with gas by the suction

in the inlet chamber L. The shaft H is adapted to be driven by any suitable motive power which may be mechanically connected by means of the flange u.

I claim:

25 A combined exhauster and tar extractor for gas comprising a casing, an impeller rotatably mounted in said casing, a diffuser extending radially from said impeller and curved at its outer end, an annular chamber in said casing adjacent said diffuser and a slot in alignment with the radially extending portion of said diffuser adjacent said curved end and leading into said annular chamber whereby tar is projected from said diffuser into said slot.

30 In testimony whereof I have signed this specification.

LEWIS C. BAYLES.
